UNITED STATES PATENT OFFICE.

GEORGE W. TURNER, OF MINNEAPOLIS, MINNESOTA.

TUB-SEAT.

1,139,824.

Specification of Letters Patent.

Patented May 18, 1915.

Application filed September 23, 1914. Serial No. 863,153.

To all whom it may concern:

Be it known that I, GEORGE W. TURNER, a citizen of the United States, residing at Minneapolis, in the county of Hennepin 5 and State of Minnesota, have invented a new and useful Improvement in Tub-Seats, of which the following is a specification.

My invention relates to a seat which is designed for use in conjunction with ordinary wash tubs.

The objects of my invention are, first, to provide a suitable seat for the person compelled to take his baths in the ordinary wash tub, second, to afford protection 15 against water being splashed on the floor, third, to provide a means of rinsing one's self without the necessity of changing tubs or emptying the one in which the bath was taken, and fourth, to provide a folding support for the seat which is adjustable in 20 height, so that the seat can be used in connection with a tub of any height.

To these ends my invention comprises the details of construction and combinations of 25 parts, which will be hereinafter more particularly described and set forth in the claims.

In the accompanying drawings forming part of this specification, Figure 1 is a back 30 view of the appliance with the legs in normal position to support the seat when in use, one leg being shown in section, on line 3-4, Fig. 2; Fig. 2 is a bottom view as it appears with one leg removed entirely and 35 the rubber foot of the other taken out; Fig. 3 is a side view as it appears with both legs removed, the brace being only partially shown when locked in normal position, and the cleat in section taken upon the line 40 1-2, Fig. 2, and Fig. 4 is a perspective of my invention in use on a tub.

Similar letters refer to similar parts throughout the several views.

The seat A is formed from a single piece 45 of material with an outwardly flaring side B, which is of substantially even height extending around the outer edge. The seat may be made out of a number of pieces of material when desired, but its side is of 50 even height substantially throughout its length for the purpose of forming a guard near the forward extremities of the seat, which prevents water from splashing and running over the side of the seat outside of 55 the tub. The upper edge of the side and the forward edge of the seat which is adapt-

ed to overlap the rim of the tub are edged with wire such as *a*, said wire being fastened by rolling the material of the seat over it and serving to assist in preventing the seat from slipping off of the tub when placed on its rim as illustrated in Fig. 4. The bottom of the seat is provided with stops H-H and E, which coöperate with the rolled edge of the seat to hold the forward edge of the seat upon the rim of the tub. Fastened across the bottom of the seat near its outer portion away from the tub is a cleat F, which is formed with three downwardly projecting lugs *g-g-g*. Secured to the end lugs such as by bolts *h-h* are a pair of legs C-C, said bolts acting as pivots to allow the legs to swing up against the bottom in folded position. The stop E is in the form of a plate secured to the bottom of the seat having a downwardly extending spring tongue *e*, which is formed at its outer and lower end with a pair of oppositely disposed notches *i-i*. The tongue *e* acts as a bearing for a brace 80 D, said brace consisting of a rod bent between its ends into V shape, having its apex loosely pivoted in the centrally disposed lug *g*, and the extremities of its bars pivotally secured over bolts *f-f* passing through the 85 collars or clamps G-G, which embrace the lower ends of the legs C-C. The tongue *k* has a tendency to spring upwardly with its notches engaged over the bars of the V shaped brace when the legs are in normal 90 or superior position. By pressing the tongue downwardly it is disengaged from the brace and the legs may then be turned into folded position against the bottom of the seat. This construction allows the legs 95 to fold while the brace remains attached to the seat body and legs, thus causing the parts to assume compact form when folded without any parts protruding in danger of becoming broken. Each of the legs is 100 formed with a tubular portion *b* into which an extension leg section *d* is slidable, said extension leg being also of tubular form and adapted to hold at its lower end a resilient rubber foot *e*. The 105 lower portion of the tubular portion *b* of the main leg C is slotted longitudinally at *j* and the collar or clamp G, which embraces it is adapted when the bolt *f* is tightened to contract the tubular portion of the main leg 110 tightly around the extensible leg section, thus holding the latter in stationary posi-

tion. By adjusting the bolts $f-f$, the extensible portions of the legs may be varied in position to support the outer portion of the seat at any desired elevation according to the height of the tub with which the seat is employed.

The construction described is simple and effective and is adapted to provide a seat which will prevent any water from running or splashing over its sides, and also enables the seat to be securely adjusted on the tub at any desired elevation. A loop or eye is fastened near the upper edge of the flaring side for the purpose of providing suitable means for hanging the appliance up when folded and not in use, said fastener I being secured to the seat by a clip such as m .

In accordance with the patent statutes, I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. A tub seat, comprising, in combination, a seat body having an edge adapted to engage over the rim of a tub, a pair of legs hinged to the lower outer portion of the seat, a brace consisting of an arm having its

ends secured to the outer extremities of said legs and the portion between its ends shaped at an angle and hinged to the bottom of the seat, and a lock member adapted to releasably engage the angle portion of said brace to hold the legs in standing position, and permitting them when the lock member is released and while said brace remains attached to said legs and seat body to fold against the seat.

2. A tub seat, comprising, in combination, a seat body having an edge adapted to engage over the rim of a tub, a pair of legs hinged to the lower outer portion of the seat permitting them to assume standing or folded position, the lower portions of said legs being tubular and split to permit said tubular portions being contracted, extensible elements secured in the tubular portions of said legs, clamps over the slit ends of said tubular portions to hold the extensible leg sections in adjusted position, a brace arm having its ends secured to said clamps and shaped at an angle between its ends, a fastener on said seat in which the angle portion of said brace is hinged permitting the legs to fold and a spring lock member adapted to releasably engage said brace and hold said legs in standing position.

In witness whereof, I have signed my name to this specification, in the presence of two subscribing witnesses.

GEORGE W. TURNER.
